PROCESS FOR MANUFACTURING BOXES
FROM WOOD AND BOX

Walter Klein, Cologne-on-the-Rhine, Germany

Application February 23, 1933, Serial No. 658,119

6 Claims. (Cl. 93—51)

This invention relates to a new process for manufacturing boxes of thin strips or sheets of wood or the like, and to boxes manufactured by this new process.

5 In the processes as hitherto used wooden strips or sheets are laid transversely one upon another and at the bottom they are united by means of clamps. The extending parts are then bent upwards and the bent edges connected by metal strips laid across them. If it is required to have 10 the adjacent edges tightened they are connected by metal strips pressed or clinched into the adjacent parts or they are joined by a strip of textile fabric or paper stuck across them.

15 According to this invention all means of connection such as clamps, clinching irons, strips of metal or textile fabric etc. are avoided. This has the advantages that not only the process of manufacture will be far simpler, quicker and 20 cheaper but also the product will be rendered cheaper and more satisfactory and it will become absolutely tight, automatically and without any further means or addition.

According to the new process of manufacture 25 the boxes are made from thin sheets, plates or strips of wood or the like, especially of plywood. The strip or sheet is cut to the necessary dimensions and all such parts which are superfluous while the side-walls are being bent upwards to 30 close the box are cut away out of the sheet. But the cutting is executed in such a manner that a small quantity of wood is left over at the edges beyond that which is required for closing the box and causing the edges of the bent side-walls 35 to touch one another in order to be joined.

In the accompanying drawing Fig. 1 is a perspective view of a handpress, Fig. 2 shows the plywood blank flat and in dotted lines folded, Fig. 3 is a complete box. 1 is the stamp of the 40 press, 2 the mould in which the stamp enters when descended, 3 the blank plywood sheet and 1a is the wood strip put around the stamp, if the box shall be more stable which strip is fixed to the walls of the blank when folded whilst 45 pressing.

The sheet of plywood is then moistened in order to facilitate bending and it is then laid upon a moulded block or last which must be heated. Then a stamp or plunger of any desired 50 or suitable construction is applied which when descending presses the sheet of plywood into the mould of the block and against its inner walls which is shaped according to the form which the finished box or the like has to assume. The edges 55 of the sheet are then bent upwards by this pro-

cedure to form side walls which with their edges are pressed against one another. The stamp also must be heated.

By this manner of procedure the sheet of plywood is brought into the desired form of box. 5 The cut edges of the sheet will abut one another. But as there is a small surplus of material at the cut edges these will not only abut one another but they will be fitted into each other, i. e. they will become matted and welded together and 10 forced into each other to a certain degree by the pressure of the stamp so that the finished article will show no seam but only smooth corners, and it will have the appearance as if the box had been made out of a single piece of wood and the 15 side-walls were integral with one another at the corners. The stamp is then retired and the box can be taken out of the mould and is at once ready for use.

The walls of the box being of plywood are thin. 20 If therefore, it is required to stiffen or thicken the walls of the box it may be lined inside with the same or a similar additional material. In this case another sheet or strip of thin wood is laid around the stamp. The lower surface of 25 this sheet is provided with a paste or adhesive matter. Then the stamp when descending presses this additional sheet into the hollow of the main part and against its inner walls where they become tightly joined and stuck together. 30 The dimensions of this additional sheet may be the same, or a little smaller or a little higher than those of the main sheet. In the latter case the edges of the walls of the additional or inner part will project above the edges of the walls of 35 the main or outer part in the finished box. The moisture contained in the paste and in the plywood evaporates by the heat of the block and of the stamp so that when the finished article is 40 taken out of the mould it is ready for use.

What I claim and desire to secure by U. S. Letters Patent is:

1. Process for manufacturing boxes from a sheet of plywood which consists in placing the 45 sheet suitably cut-out and moistened upon a heated moulded block and pressing it by means of a heated stamp into the mould in such a manner that the edges of the sheet are bent upwards to form sidewalls which are then pressed against 50 the inner walls of the mould and with their edges touching one another.

2. Process for manufacturing boxes from a sheet of plywood which consists in placing the 55 sheet suitably cut-out and moistened upon a

heated moulded block and pressing it by means of a heated stamp into said mould in such a manner that the edges of the sheet are bent upwards to form side-walls which are then pressed against the inner walls of the mould and with their edges touching one another, providing the edges of the sheet with a small surplus of material when cut and forcing them into each other by the pressing.

3. Process for manufacturing boxes from a sheet of plywood which consists in placing the sheet suitably cut-out and moistened upon a heated moulded block and pressing it by means of a heated stamp into the mould in such a manner that the edges of the sheet are bent upwards to form side-walls which are then pressed against the inner walls of the mould and with their edges touching one another, an additional sheet of wood being laid round the stamp and pressed by the same procedure into the interior of the main part of the box and against its inner walls to be united therewith.

4. A box from a sheet of wood suitably cut out and pressed into the desired form in a mould by a stamp, the edges of the sheet when cut being provided with a small surplus of material so that

they are forced into each other by the pressure and smooth corners of the finished box are obtained.

5. A box from a sheet of plywood suitably cut out and pressed into the desired form in a mould by a stamp, the edges of the sheet when cut being provided with a small surplus of material so that they are forced into each other by the pressure and smooth corners of the finished box are obtained, the interior of which being lined with an additional sheet of a similar material.

6. A box from a sheet of wood suitably cut out and pressed into the desired form in a mould by a stamp, the edges of the sheet when cut being provided with a small surplus of material so that they are forced into each other by the pressure and smooth corners of the finished box are obtained, the interior sidewalls of which being lined with an additional sheet of a similar material, the dimensions of this additional sheet being a little higher than the sidewalls so that in the finished box the edges of the walls of the additional inner part will project above the edges of the walls of the main or outer part.
